US0D1066527S

(12) **United States Design Patent** (10) **Patent No.:** **US D1,066,527 S**
(45) **Date of Patent:** **** Mar. 11, 2025**

(54) **EXERCISE STAND**

(71) Applicant: **Coulter Ventures, LLC.**, Columbus, OH (US)

(72) Inventor: **Bryan Adams**, Columbus, OH (US)

(73) Assignee: **Coulter Ventures, LLC.**, Columbus, OH (US)

(**) Term: **15 Years**

(21) Appl. No.: **29/825,374**

(22) Filed: **Jan. 31, 2022**

Related U.S. Application Data

(63) Continuation of application No. 29/750,468, filed on Sep. 14, 2020, now Pat. No. Des. 942,563, which is a continuation of application No. 29/698,994, filed on Jul. 22, 2019, now Pat. No. Des. 896,326, which is a continuation of application No. 29/646,787, filed on May 7, 2018, now Pat. No. Des. 854,637.

(74) *Attorney, Agent, or Firm* — Banner & Witcoff, Ltd.

(57) **CLAIM**

The ornamental design for an exercise stand, as shown and described.

DESCRIPTION

FIG. 1 is a top, front, right perspective view of an exercise stand showing my new design;

FIG. 2 is a top, front, left perspective view thereof;

FIG. 3 is a left side view thereof;

FIG. 4 is a right side view thereof;

FIG. 5 is a front view thereof;

FIG. 6 is a rear thereof;

FIG. 7 is a top view thereof; and,

FIG. 8 is a top, front, right perspective view of the design in FIGS. 1-7 showing additional example environment.

The broken lines depicting the remainder of the exercise stand show features that form no part of the claimed design.

1 Claim, 8 Drawing Sheets
